UNITED STATES PATENT OFFICE.

HENRY S. GOUGHNOUR, OF JOHNSTOWN, PENNSYLVANIA, ASSIGNOR TO
THE LORAIN STEEL COMPANY, OF PENNSYLVANIA.

TROLLEY.

SPECIFICATION forming part of Letters Patent No. 661,516, dated November 13, 1900.

Application filed March 21, 1900. Serial No. 9,523. (No model.)

To all whom it may concern:

Be it known that I, HENRY S. GOUGHNOUR, of Johnstown, in the county of Cambria and State of Pennsylvania, have invented a new and useful Improvement in Trolleys, (Case A,) of which the following is a full, clear, and exact description, reference being had to the accompanying drawings, which form a part of this specification.

10 My invention has relation to certain new and useful improvements in trolleys, and is designed to provide means of improved character whereby when the trolley-wheel leaves the conductor from any cause the pole will automatically assume a position where it will not come in contact with and injure or be injured by span or guard wires or other overhead structures, together with means whereby the pole may be subsequently returned to its 20 original position.

A further object is to provide a trolley-base of simple and efficient construction which shall have a minimum projection above the roof of the car, so as to permit the latter to 25 pass under bridges and other low overhead structures.

With these objects in view my invention consists in the novel construction and combination of parts, all as hereinafter described, 30 and pointed out in the appended claims.

In the accompanying drawings, forming part of this specification, Figure 1 is a side elevation of my improved trolley. Fig. 2 is a plan view of the same. Fig. 3 is a detail view showing the spring and the means for holding the same in tension and for releasing the tension, and Fig. 4 is a detail view of the resetting device.

The letter A designates an arm or bracket 40 which is swiveled to the roof of the car in any desired or usual manner, and B is the trolley-pole, which is pivotally secured between the side portions of said bracket a short distance above its lower end.

45 C is the spring which normally holds the trolley-pole in contact with the overhead conductor. This spring is coiled about one end portion of a rod D, whose opposite end portion is link-connected with the lower end of 50 the pole, one end of the spring bearing against a head or stop on the end of the rod and its

other end bearing against a slide E, into which said rod extends through one end thereof. The slide E is seated between and guided by the side portions of the bracket A. On the 55 rear end of the said slide is a catch projection F, which is normally engaged by a latch F', pivoted at f to a block F², which is seated on the bracket A and which is formed with a lug or projection f', to which is connected one end 60 of a chain G, whose opposite end is connected to the trolley-pole a short distance above its pivot. In lieu of this chain I may employ a link or other equivalent connection. The block F² is fulcrumed at its lower corner f² 65 and is held to its seat by a pin f³, whose end portions are seated in slots g of the bracket A and pressed by springs g².

H designates resetting-levers, which are pivoted at their lower end portions to opposite sides of the bracket A and are connected at their upper ends by a pivoted bail H'.

I is a transverse rod which extends through longitudinal slots h in the sides of the bracket A and which is formed with cranked end portions I', which are pivoted in the respective levers H. These levers normally lie in nearly flat positions down alongside the bracket A, as shown in full lines in Fig. 1, being returned to this position after operation by their own 80 gravity. If desired, however, retracting-springs may be employed for this purpose.

P designates the usual guide-rope for the trolley-pole, one end being connected to the pole in the usual manner and the other end 85 being connected to the bail H' of the resetting-lever, the intermediate portion of the rope being designed to hang down over the back of the car in position to be readily reached. A separate rope may, however, be 90 provided for the resetting-lever, if desired.

The operation is as follows: Under the normal running conditions the latch F' is in engagement with the catch projection F of the slide E, and the spring C is thereby held under compression. When, however, by any cause the trolley-wheel leaves the conductor, the pull on the chain G when the pole reaches or approaches a vertical position rocks the block F² on its fulcrum and disengages the 100 said latch. This releases the slide E, which is at once thrown toward the lower end of

the pole by the spring C, the latter thereby losing its tension. The pole now immediately drops to about the position shown in dotted lines in Fig. 1. The slide E is stopped by 5 the rod I as the pole approaches this position, so that further drop of the pole by its pull on the rod D tends to compress the spring C, and thereby cushion the impact of the pole. To reset, a pull on that branch of the rope 10 which is connected to the bail H raises the levers H, thereby causing the rod I to push backward against the slide E and force the latter back to its original position, where it is automatically caught and held by the pivoted 15 latch F'. The rod I by reason of its cranked ends exerts a push in a direct line upon the slide throughout its upward movement of the levers, and a very effective leverage is obtained for restoring compression to the spring. 20 The latch device being seated in the manner described remains in position to automatically engage the catch F, notwithstanding the fact that at the time the engagement is effected there is some tension in the chain G, 25 which would otherwise tend to hold said latch in raised position. The described details of said device are, however, not essential to my invention, since various forms of latch devices may be used. Nor do I wish to be limited 30 in other respects to the mechanical details of construction and arrangement which I have herein shown and described, as these may be varied without departing from my invention as it is pointed out in the following 35 claims.

Having thus described my invention, what I claim, and desire to secure by Letters Patent, is—

1. In a trolley, the combination with a pivoted trolley-pole, of a spring for elevating the 40 same, a slide forming a bearing for one end of said spring, a rod having a bearing for the opposite end of the spring, and connected to the said pole, a latch device for said slide, 45 and a connection between the pole and said latch device for tripping the latter when the pole assumes a certain position.

2. In a trolley, the combination with a pivoted trolley-pole, of a spring for elevating the 50 same, a slide forming a bearing for one end of said spring, a rod having a bearing for the opposite end of the spring, and connected to the said pole, a latch device for said slide, 55 and a connection between the pole and said latch device for tripping the latter when the pole assumes a certain position, together with means for restoring the compression in said spring.

3. In a trolley, the combination with a pivoted pole, and a spring for holding the pole in running position, of a slide forming a bearing for one end of said spring, a latch device for said slide, and a connection between the latch device and the pole for automatically 65 tripping said latch.

4. In a trolley, the combination with a piv-

oted trolley-pole and its actuating-spring, of a slide forming a bearing for one end of said spring, a latch device for said slide, a connection between the latch device and the pole 70 for automatically releasing said device when the pole assumes a certain position, a resetting-lever engaging the said slide, and means for actuating the said lever.

5. In a trolley of the character described, 75 the combination with the pole, its actuating-spring, and a slide forming a bearing for one end of said spring, of a latch for engagement with said slide, a block to which said latch is pivoted and which is arranged to fulcrum 80 at one of its edges, spring means for holding said block to its seat, and a connection between said block and the trolley-pole.

6. In a trolley of the class described, the combination with the pivoted pole, its actuating-spring, the slide forming a bearing for one end of the said spring, a latch for holding said slide with the spring under compression, and means for automatically releasing said latch when the spring assumes a certain position, 90 of a resetting-lever engaging one end of the said slide, and means for actuating said lever.

7. In a trolley, the combination of a swiveled bracket, a pole pivoted thereto, a spring 95 seated in said bracket, a rod connected to the pole at one end and having a bearing for the distant end of the spring, a slide on said rod having a bearing for the opposite end of the said spring, a latch for securing the said slide, 100 means whereby said latch is released when the pole assumes a certain position, and means for restoring said slide to its original position after it has been released.

8. In a trolley-base, the combination with 105 a swiveled bracket, a pole pivoted thereto, an actuating-spring for said pole, a slide forming a bearing for one end of the spring, and in which the spring is seated, means for holding said slide with the spring under compression, and for automatically releasing the same 110 when the pole assumes a certain position, of a resetting device engaging the said slide to move the same in one direction, and also forming a stop for limiting the movement of said 115 slide in the opposite direction.

9. In a trolley, the combination with the bracket, and the slide mounted therein and forming a bearing for one end of the pole-actuating spring, of the connected resetting-levers pivoted to opposite sides of said bracket and the transverse rod seated in slots in said bracket and engaging one end of said slide, 120 said rod having cranked end portions pivotally secured in said levers.

In testimony whereof I have affixed my signature in presence of two witnesses.

HENRY S. GOUGHNOUR.
